AUTOMATICALLY FED THREAD ROLLING
MACHINE

James W. Batchelder, Ascutney, Vt., assignor, by
mesne assignments, to The Economy Engineering
Company, Willoughby, Ohio, a corporation
of Ohio

Application April 9, 1949, Serial No. 86,417

5 Claims. (Cl. 80—6)

1

This invention relates to thread rolling machines, and particularly to machines adapted for operating either on cylindrical or on tapered work pieces such as pipe plugs or grease fittings. One object of the invention is to provide a work feed which will operate with either conical or cylindrical work pieces and which will greatly increase the output of the machine. A further object is to provide a thread rolling die system for tapered work in which there will be no more slip between the dies and the work than in cylindrical work systems. A further object is to provide simple mechanism for varying and controlling the rate of penetration of the dies into the work, and in particular to provide for ready adjustment to a condition giving a large number of work turns per cycle so that hollow or socketed work pieces may be rolled without distortion or cracking. Additional objects will appear from the following description and claims.

The invention will now be described with reference to the accompanying drawings, in which

Fig. 1 is a vertical section through the machine, taken on line 1—1 of Fig. 3;

Fig. 2 is a section on line 2—2 of Fig. 1;

Fig. 3 is a section on line 3—3 of Fig. 1 and the line 3—3 of Fig. 4;

Fig. 4 is a section on line 4—4 of Fig. 3;

Fig. 5 is a section on line 5—5 of Fig. 3;

Fig. 6 is a view similar to a portion of Fig. 3 but showing the machine set for operation on cylindrical work pieces;

Fig. 7 is an enlarged detail, partly in section on line 7—7 of Fig. 6;

Fig. 8 is an enlarged detail of parts shown in Fig. 6;

Fig. 9 is a section on line 9—9 of Fig. 1;

Fig. 10 is a diagram illustrating the relationship between the dies and work piece in rolling tapered threads;

Figs. 11, 12 and 13 are successive views showing stages in the delivery of a work piece by the feeding mechanism;

Figs. 14, 15 and 16 are sections respectively on lines 14—14, 15—15 and 16—16 of Figs. 11, 12 and 13;

Figs. 17, 18 and 19 are sections respectively on lines 17—17, 18—18 and 19—19 of Figs. 14, 15 and 16;

Fig. 20 is a section on line 20—20 of Fig. 16 and

Fig. 21 is a detail section corresponding to a portion of Fig. 14 but with the transfer still moving upwardly.

The machine is carried on a lower frame 1 (Fig. 1) above which is an upper frame 2. The

2

upper and lower frames are joined by side frames 3 (Fig. 5) recessed into them, thus preventing inward buckling of the frames 1 and 2 with consequent binding of the toggle mechanism. Keyed at 4 to the upper and lower frames are heads 5 and 6 which serve as abutments against which the toggle mechanism exerts its pressure. Head 6 has a shaft 7 extending through it, shouldered at 8 to engage the head on one side and having a hand wheel 9 pinned to it so as to engage the head on the other. The shaft can therefore rotate but cannot move lengthwise. It is threaded at 10 into a slide 11 which carries one of the dies in a manner to be described, and serves to adjust the spacing of the dies for different sizes of work pieces. A graduated pointer 12 cooperates with graduations on the handwheel to indicate the setting.

To head 5 is pinned at 13 a yoke 14. A second yoke 15 is pinned at 16 to a slide 17 carrying the second die. Yokes 14 and 15 are pinned together at 18, the latter pin also engaging one end of a forked link 19 pinned at 20 to a rocker 21 carrying a cam roll 22 which is held by a spring 23 against a toggle operating cam 24. Cam 24 is keyed to a shaft 25 to which a gear 26 is also keyed. This gear meshes with a second gear 27 of equal size keyed to a second cam shaft 28 driven by gears 29 and 30 from a drive shaft 31 extending across the machine and driven as will be described. A tapered collar 32 (Fig. 9) is also keyed to cam shaft 28 and receives a cam 33 which is held in adjusted position by a clamp 34. This cam operates the work feeding and positioning mechanism which will be described later, and because of the 1:1 ratio of gears 26 and 27, is always in synchronism with cam 24.

Slides 11 and 17 are each provided with a circular track 35 (Figs. 3 and 6) in which a rail 36 on a die head 37 is held for a limited swinging movement by a clamp plate 38. Each die head is provided with lugs 39 (Fig. 1) in which a pin 40 is journaled. A screw 41 (Fig. 3) is held by collar 42 against longitudinal motion in a flange on the slide and is threaded through pin 40 so that by turning the screw the angle of the die heads may be changed from the parallel position of Fig. 6 to an angular one such as is shown in Fig. 3, the angle being determinable by graduations on the rail as shown in the latter figure. Each die head has an outboard portion 43, between which and the main part of the die head a die 44 is keyed on a spindle 45. One spindle (Fig. 7) is provided with a flange 46 opposed to a flange 47 on a universal joint 48, the flanges

being held in adjusted position by clamp rings 49, 50 having tightening bolts 51. The other spindle may be permanently connected to its universal joint 52 by a pin 53. In this way the spindles may be adjusted relative to each other so that the threads on the dies may be brought into registry. In Fig. 6 the spindles are shown parallel and provided with cylindrical dies, while in Fig. 3 the spindles converge and are provided with conical dies.

The universal joints 48 and 52 are each connected by a shaft 55 to universal joints 56 which are slidably keyed at 57 to shafts 58 journaled in a gear box 59. Each shaft 58 carries a gear 60 meshing with a common pinion 61 on a drive shaft 62 which may be driven by a motor 63 (Fig. 4) through a belt connection 64. One of the shafts 58 is provided with a sprocket 65 coupled by a chain 66 with a sprocket 67 on the toggle drive shaft 31. To centralize the gear box with respect to the die heads a positioning screw 68 may be placed between it and its supporting frame. This is not always necessary but assists in maintaining the relative velocity between the two dies constant throughout a revolution. Due to the use of double universal joints on each spindle drive the speed of each spindle is made substantially constant; although, due to the fact that the angles between each shaft 55 and its respective shaft 58 and spindle 45 are not equal when the die head is in angular position (Fig. 3), there is a small variation in speed which can generally be ignored since both heads are similarly affected. If the position of the slide 11 be varied, however, the angles and thus the variations in speed will not be the same in the two cases unless the gear box is shifted to bring the drives for the two heads into symmetry, and the positioning screw 68 is desirable for this reason.

For rolling tapered threads the dies are in the form of cones the diameters of which at any point are integral multiples ND of the diameter D of the work at that point. The value of N is not critical, but it must be an integer. For practical reasons N usually has the same value for both dies, but it may have different values if the angular velocity of the spindles is made such that the surface speeds of the two dies are the same. If the work is to be single threaded the dies are multiple threaded with N threads; if the work is n -threaded the dies will have $n \times N$ threads. The conical pitch surface formed on the work pieces and the conical pitch surfaces of the two dies lie tangent in a common plane including the axes of the dies, and have their apexes at the same point. Since the ratio of pitch diameters of a given die and of the work piece is N and therefore the geometrically consequent relationship of the respective apical angles A and B is $\sin(A/2) = N \sin(B/2)$, for the case of dies of like size and speed, shown in Fig. 10, when the angles are small, it may be taken that the included or apical angle A of the die cones is N times the angle B of the work-cone, and that the included angle C (i. e. $A+B$) between the axes of the dies is $(N+1)B$, and the angle each spindle is displaced from parallel position is exactly half of this. With these proportions and with the threads on one die adjusted (as by clamp rings 49, 50) so as to be exactly 180° out of phase with those diametrically across the work piece on the other die, work may be introduced between the dies at any time, and when once grasped by the dies will be held by

them firmly in constant axial position as it and the dies rotate. Furthermore, the speed of the surface of the die is, with this arrangement of cones, exactly the same as the surface speed of the work so that there is no slippage.

The dies are apart at the time when the work blank is placed between them, and are then closed to a position which is determinable by the handwheel 9. Gears 29 and 30 are readily removable so that they can be replaced by others having a different ratio. The approach of the dies in one revolution of the work piece can thus be varied to control the rate of the penetration of the dies into the work. It is generally unnecessary to change cam 24 for this purpose. For solid work pieces a relatively high rate of penetration can be used, the threading operation being completed in a relatively few number of work turns; while on hollow work the penetration rate should be slow.

Above the dies are tracks 69 coming from any suitable magazine, the construction of which is not important here. The tracks are shaped to the particular work blank w , which in this case is shown as a frustum of a cone with chamfered ends. The lower end of the tracks are cut away at 70 to receive double-ended escapement blades 71 fastened to pins 72 which have at their ends fingers 73 connected by a spring 74 tending to draw the lower ends of the blades within the track. To actuate the blades 71 a cam bar 75 is mounted on a rocker 76 pivoted at 77 to a bracket 78. The bracket is adjustably clamped to a dovetail 79 parallel to the axis of the work and itself clamped to a dovetail 80 extending crosswise of the work. The latter dovetail is formed on the top of a post 81 sliding in a bearing 82 in the bed and pressed downwardly by a spring 83. A roll 84 on the lower end of the post engages a block 85 held in position by an adjusting screw 86 in one end of a double lever 87, 88. The lever is pivoted to the frame and bears a cam roll 89 riding on cam 33 previously mentioned. The rocker 76, and another one 90 similar to it except that it carries no cam bar, are each formed with a socket or notch 91 to engage the work blank by its ends, and together form a transfer for taking a blank from the tracks and positioning it between the dies. The two rockers are pressed towards each other by springs 92 so that they grasp the work blank yieldingly. The action of the cam bar on the ends of fingers 73 will be clear from a comparison of Figs. 11, 12 and 13.

The cycle of operations is shown in Figs. 11 to 19, in which Figs. 11, 14 and 17 show the uppermost position of the transfer, Figs. 12, 15 and 18 an intermediate position in its downward travel, and Figs. 13, 16 and 19 the position where the work blank has been placed in alignment with the dies and the latter have closed in on them. As the transfer rises, beveled edges 93 (Fig. 21) above sockets 91 strike the blank w and cause the rockers 76, 90 to spread so that their socketed portions may pass over the ends of the blank and ultimately spring into holding engagement with it as shown in Fig. 15. The transfer then descends and at the same time the dies are separated by the toggle, allowing the finished blank w' to drop out as in Fig. 12. It should be noted that there is no obstruction, such as a work rest, which prevents the work from dropping out. The lowermost position of the transfer (Fig. 13) brings the blank into the plane of the axes of the dies, a position to which it can be adjusted

accurately by screw 86. At least one finger of the transfer should in this position lie at least in part between the dies so that threads will be formed all the way to the end of the blank. While the transfer holds the blank in this position the dies move in, due to the steady rotation of cam 24. Once the dies have engaged the work blank they hold it so firmly that the transfer can be moved upwardly, its sockets 91 passing over the end of the work with no danger of dislodging it from the dies.

The operation of the escapement is as follows. Starting with a blank resting on the left hand bottom blade and the stack of blanks supported by the right hand top blade (Fig. 19), the transfer rises as soon as the blank it has carried down is grasped firmly by the dies. The cam 75 acts on the left finger 73 to rotate its blades 71 clockwise sufficiently to bring the top blade into blocking position under the blanks in the track and the lower blade to a position where it barely supports the blank it is holding. The right hand blades are also rotated clockwise by cam 75, but at a slightly later time. Soon after the left top blade is in blocking position the right hand top blade moves out to release the stack of blanks, which drops (Fig. 17) until its lowest blank strikes the left top blade. By the same motion the right bottom blade is moved over the blank in the escapement to hold it against the upward force exerted by the transfer as it moves against the blank (Fig. 21). The upward stroke of the transfer ends as soon as it has grasped the blanks firmly.

The transfer then starts downwardly, pulling the blank past the left bottom finger, which can yield on account of spring 74. The right hand blades this time move first, rotating counter-clockwise to the position of Fig. 18 in which the upper blade supports the blank next to the bottom in the stack, the bottom one being held by the upper blade of the left hand set. These latter blades now rotate counter-clockwise (Fig. 19) so that when the upper blade releases the blank the lower blade catches it.

The toggle cam 24 has its profile so shaped that, taking into account the properties of the linkage it operates, the number of work turns given to work pieces of various depths of thread will be substantially constant. The handwheel 9 is adjusted so that at the end of the toggle stroke the pitch circumference of the dies will be separated by the pitch diameter of the thread. When contact is initially made between the work and blank the outer die surfaces are of course separated by the blank diameter, which is roughly the pitch diameter of the finished work piece. The distance the toggle-carried die moves beyond this is equal to the thread depth. Thus for a fine thread the die would meet the blank later in the cycle than for a coarse thread, and the blank would not have so many turns during actual rolling. The profile of the cam is therefore chosen so that, in combination with the slowing down of the die on account of the normal action of a toggle approaching the end of its stroke, the speed of approach of the die will be reduced sufficiently so that coarse and fine threaded work pieces will have approximately the same number of turns during rolling.

The transfer cam 33 is circumferentially adjustable so that the transfer may be caused to arrive at the plane of the die axes after the completed work piece has been dropped from between the dies, but before the dies again close.

Since coarse threaded pieces have a less proportion of the cam cycle available for feeding, if the transfer cam is adjusted for coarse work it will also serve for fine. The stroke of the toggle remains constant, being equal to the depth of penetration for the deepest thread that is to be handled plus the necessary clearance for discharge and reception of a work piece, and the toggle cam 24 need not be adjusted when the type of the work piece is changed. If special types of work be encountered, such as hollow screws, the relation between the number of revolutions of the work and the advance of the dies can be varied by the change gears 29, 30.

For changing from one size of work piece to another it is necessary to change the dies 44, and in order to do this the outboard member 43 must be removed. This member fits in a groove 94 in which it is held by screws 95, and carries a bearing 96 (Fig. 8) for the spindle 45. The bearing may be of the ball, needle or roller type, but for simplicity is here shown as a simple bushing. It is preferably provided with snap rings 97 which attach it permanently to member 43, so that when the latter is removed from the machine for the purpose of changing dies the bearing will be removed with it and will be protected against dirt and injury. When replaced on the machine the bearing is pressed against the die, which rests against a shoulder 98, by a tap bolt 99 acting on a washer 100.

It is of considerable importance that the work blanks should always be introduced between the dies at the same axial position. When the work blank is headed careful positioning is required so that the heads themselves do not sometimes get between the dies even though the threads run nearly to the shoulder. Also where the work is tapered it will readily be seen that the pitch diameter would vary if the blanks did not all come to the same axial position. To insure the constancy of this axial position the spring 92 under finger 76 is made a little stronger than the corresponding spring under finger 90. Finger 76 will thus always come to rest in a constant position against a stop formed by the check nut 101 which holds it against the spring, and finger 90 can shift to take care of small differences in work length. The small end of a tapered blank is preferably chosen as the one to be kept in standard position, since tapered articles such as pipe plugs are generally gauged at this end.

What I claim is:

1. A thread rolling machine having a pair of slides mounted for relative reciprocating movement to and from each other; a die head carried on each of said slides; a spindle carried in each of said die heads, the axes of the spindles being disposed for movement in a common plane upon relative movement of said slides; a threading die mounted on each spindle; driving means for rotating the spindles in the same direction; a work blank magazine disposed above the said dies and provided with an escapement mechanism for separating the lowermost work blank from the others; a transfer mechanism for removing the lowermost blank from the magazine and positioning it between the dies with its axis in said common plane, said transfer mechanism including a base below said dies, a pair of opposed fingers pivotally mounted on said base and extending upwardly beyond the said common plane and biased toward each other for grasping a work blank at its ends, at least one of said fingers being disposed between the dies when the transfer has

a blank positioned with its axis in said common plane, a work blank end gaging surface provided on said one finger for gaging the axial position of one end of a blank, and means to reciprocate said fingers between said magazine and dies; and slide actuating means for causing said relative reciprocating movement of said slides to effect gripping, penetration and release of a work blank between said dies, said slide actuating means being driven in timed relation with said transfer mechanism to effect gripping of a blank when said transfer mechanism positions the blank with its axis in said common plane.

2. A thread rolling machine as claimed in claim 1, wherein said fingers, base, and actuating means of the transfer mechanism are disposed to allow free discharge of a finished work blank beneath said dies.

3. A thread rolling machine as described in claim 1, wherein said die heads are adjustably mounted to said slides for varying the relative angular disposition of the spindle axes in said common plane and wherein said base of the transfer mechanism includes a pair of adjustable mountings for adjusting the position of said fingers in two directions parallel to said common plane.

4. In a thread rolling machine for rolling threads on a conical work blank, a structure as described in claim 1 having conical threaded dies with axes in a common plane and at an angle to each other, adjustable die heads for adjusting the dies relative to each other to set the interaxial angle substantially equal to the sum of the apical angle of the work piece to be threaded and the apical angle of one of the dies, said slides being

movable relatively toward each other to bring the apical points of the dies into coincidence in penetrating a work piece, and said transfer mechanism being adjustable parallel to said common plane to position a work blank with its axis passing through the point of coincidence of the apical points of the dies.

5. A thread rolling machine as claimed in claim 1 in which said transfer comprises opposed fingers 10 spring biased toward each other to grasp the work blank at its ends, the finger having the work blank end gaging surface being provided with a stronger spring than the other and with a stop to limit its motion toward the other finger, whereby by the work blank will be carried between the dies with one end in a constant position irrespective of minor variations in the lengths of the blanks.
